SIGNORS TO OSWEGO FALLS CORPORATION, OF FULTON, NEW YORK, A CORPORA-
TION OF NEW YORK

EXTERIOR SLIP COVER FOR CONTAINERS

Application filed February 15, 1927. Serial No. 168,335.

The object of this invention is the production of economical improved slip covers for containers; and further objects and the detailed nature of the invention will be readily understood by those skilled in the art in the light of the following explanations of the accompanying drawings that illustrate what we now believe to be the preferred mechanical expression or embodiment of our invention from among other forms and steps within the spirit and scope thereof.

10 The invention consists in certain novel features in structure and combination as more fully and particularly described and specified hereinafter.

15 Referring to the accompanying drawings forming part hereof:—

Fig. 1 shows our improved cover in side elevation on a container.

20 Fig. 2 shows the cover and a portion of the container in vertical section.

Fig. 3 is a detail enlarged side elevation of the cover.

25 Figs. 4 and 5, show apparatus in vertical section illustrating various steps in the method of producing our said covers.

Fig. 6 is a vertical section on an enlarged scale showing a portion of the completed cover before removal from the die or form in which 30 the exterior paper band and the drawn flanged paper cap are assembled.

35 The friction slip paper or like material cover of our invention consists of a flanged paper imperforate disk 1, having an approximately smooth-surface cylindrical annular flange 2, and an exterior unbroken non-expansive concentric strong paper or like material cylindrical band 3, surrounding the flange 2, the disk and exterior band constituting 40 a united permanent assembly.

45 Although it is perhaps difficult to so illustrate by drawings, the cap 1, 2, is drawn from a flat circular disk 1^a, of relatively thin flexible cheap sheet paper, while the unbroken band or cylinder 3, is preferably relatively thick in radial cross section and relatively stiff or rigid and strong or non-elastic against forces tending to expand the same.

50 This exterior band or cylinder 3, is preferably strongly constructed of secured overlying

ing sheet paper plies or of secured sheet paper laminations. The bands 3, of the desired length are usually composed of cross sections cut from elongated tubes made on suitable paper tube winding or forming machines by spirally winding and pasting together several paper bands or by convolutely rolling a sheet of paper into a number of spirally wound convolutions adhering together to form a strong tube that can be severed transversely into strong stiff bands 3.

55 In the completed slip cover, the lower edge of the surrounding band 3, is preferably approximately flush with the lower edge of the disk flange 2, and the length of the band is approximately equal to the length of the cylindrical portion of the disk flange 2, with the imperforate top wall of the cover formed by the disk, preferably flat except at its annular circumferential portion where it comes down to its cylindrical flange within the band, thereby giving the appearance of a cover with an apparently dome shaped top, although we do not wish to so limit all features of our invention.

65 The end in view is to produce a paper material slip cover that is economical in cost and that can be economically made under quantity production methods, and yet a cover that is of sufficient stability as to form and of strength and durability for use in closing certain kinds of containers, particularly one time use paper containers of exteriorly cylindrical formation or tapered paper containers, such as 4, Figs. 1 and 2, having an exterior cylindrical top rim 5, although we do not wish to so limit our invention.

70 The stiff strong encircling band 3, constitutes the backbone or stiffening frame or form structure of the completed staple cover, and thereby enables us to employ the more or less flimsy drawn flanged paper material disk 1. Such flanged paper disks are more or less flimsy and unstable as to permanence in form, particularly as the flange thereof tends to flare and return to the original flat form of the paper sheet and this tendency is increased by the presence of moisture. By combining this flanged disk with the retaining form 3, as a permanent part of the slip cover assem-

bly, we overcome the hereinbefore noted difficulties and produce an exceedingly economical slip cover that is sufficiently staple and stiff or rigid and permanent in form for the purposes of our invention.

5 The retaining form constituting band 3, and the cap flange can be united by adhesive, but we preferably so drive the cap flange into such band 3, under such pressure that the 10 flange and band are in effect permanently united and approximately welded or merged together by the contracting tendency of the band and the expanding tendency of the flange, as the cap flange is contracted and the 15 band expanded by the method we follow in assembling the flanged disk 1, 2, and form constituting band 3.

For instance, Figs. 4, 5 and 6, more or less diagrammatically illustrate mechanism that 20 can be employed in the production of the slip cover 1, 2, 3.

With reference to such mechanism, 10, is a suitable base or bed on which vertical cylinder or housing 13 is secured. The ring 25 die 9, is carried by and depends in this cylinder 13, with a flat horizontal top surface of the bed 10, forming a floor a distance below the open lower end of the ring die 9. The cylinder 13, and the bed 10 are formed to 30 provide a horizontal radial passage or slide-way through the cylinder 13, along the top face of the bed and diametrically across the lower end of the ring die 9, for slide 11. The end of this slide is formed with a circular 35 vertical opening 8, extending completely therethrough, of approximately the same diameter as the internal diameter of the lower end of the ring die, and this opening 8, registers and is alined with the vertical axis of 40 the ring die when the slide is in operative position, i. e. at its limit of movement to the left in the disclosure of Figs. 4 and 5. This opening 8, forms a ring and forming die and a holder for the paper band or cylinder 3, into 45 which the flanged paper cap 1, 2, is to be driven from the drawing dies and finally formed. To hold and carry the paper band 3, the ring die 8, in slide 11, is formed with a vertical cylindrical bore the internal diameter of which is equal to the external diameter of the band 3, so that the band can be 50 slipped down into said bore from the top with its lower edge resting on annular horizontal ledge or shoulder 12, and with its upper edge flush with or below the horizontal top surface of the portion of the slide that forms the ring die. The lower end of the bore of ring die 8, from shoulder 12, to the bottom face of the slide, is concentric with the 55 portion of the bore above shoulder 12, and is slightly less in diameter, i. e. of a diameter to shape the circumferential portion of the cover disk 1, 2, that extends above the band 3.

A vertical plunger 6, is arranged above in 60 vertical alinement with ring die 9, and this

plunger is formed to constitute the reciprocating die of a set of cap drawing dies, and to cooperate with ring die 9, in drawing the flat sheet paper circular disk 1^a, spanning and resting on the upper end of ring die 9, into 65 flanged cap form. The lower end of the plunger 6, is of reduced cylindrical form 8^a, to annular concentric overhanging shoulder 7, to receive the ironed out and drawn flanged cap and drive the same into the paper band 3, in ring die 8, and in effect constituting the 70 cap flange shaping surface of said ring die 8. The drawing dies are formed to gather, compress, and iron out the surplus paper material due to flanging the disk 1^a, to produce 75 a smooth faced flange 2, and under great pressure to drive and swage this flange into the band 3, and thus compress the same tightly thereinto putting the band under expanding tension. When the descending plunger 80 completes its operation of driving and shaping the flanged cap into the band 3, the lower end of the plunger forms and shapes the part 85 of the cap below the band and presses the cap top between the parallel flat end face of the 90 plunger and top face of the bed 10.

When the plunger has withdrawn on its upward stroke, the slide 11, is withdrawn from the dies, and the completed cover 1, 2, 3, is pressed upwardly from the slide and 95 removed. Another paper band 3, is then positioned in the die 8, in the slide and the slide is then returned to operative position within the dies, as indicated by Fig. 4, wherein the slide is shown on its way back to operative 100 position carrying a paper ring 3, in its die 8.

What we claim is:—

As a new article of manufacture, an exterior slip cover for paper and other cans, consisting essentially of a relatively-flimsy paper disk having a smooth surface ironed cylindrical flange, and a relatively strong stiff non-expansile paper band united to and exteriorly surrounding said flange and of approximately the same length as and terminating flush with the lower end of said flange, 105 whereby said cover is adapted to slip on the exterior surface of a can with approximate air tight contact to provide an approximate liquid tight can closure.

Signed at Fulton, county of Oswego, State of New York, this 11th day of February, 1927.
